pany, Inc., Wilmington, Del., a Corporation of
Delaware

Original application November 1, 1916, Serial No.
128,839. Divided and this application filed
March 31, 1921. Serial No. 454,718

4 Claims. (Cl. 196—108)

This invention relates to an improvement in an apparatus for treating hydrocarbons and refers more particularly to an apparatus used for converting relatively heavy hydrocarbons into 5 lighter hydrocarbons preferably of a gasoline-like nature, and is a division of my application in the United States Patent Office Serial No. 128,839, filed November 1st, 1916.

Among the salient objects of the invention is 10 to provide an apparatus whereby the hydrocarbons are treated continuously as distinguished from one in which they are treated intermittently, thereby not permitting a fresh supply of hydrocarbon oil to be continuously fed to the 15 apparatus. Also the result, that is, the distillate produced, is of better quality and more uniform.

Among other objects of the invention is a much 20 increased economy of operation not only in fuel consumption but in the quantity of oil that can be treated at a given time.

A further object is that when operated continuously the temperature can be maintained 25 substantially constant for relatively long periods of time instead of alternately heating and cooling, the latter conditions rapidly deteriorating the apparatus and shortening its life to a marked degree. Also with a relatively constant temperature 30 and pressure there is less strain on the pipes and lead lines.

In the drawings:

Fig. 1 is a general view of the apparatus with parts broken away to reduce the size of the drawing.

Fig. 2 is a vertical sectional view of the tube arrangement on an enlarged scale.

Fig. 3 is a view, partly diagrammatic and partly in section, of my improved apparatus.

Fig. 4 is a transverse sectional view taken on 40 lines 4—4 of Fig. 3 but on an enlarged scale.

Referring to Figs. 1 and 2, 1 designates a furnace having the usual fire box 2, above which is located a series of tubes 3, opening at their opposite ends into hollow plates 4 and 5. A plurality of baffle plates 6 and 7 are employed in the furnaces for forcing the hot gases along substantially the entire length of the tubes 3 before passing to the stack 8. Opening into the lower portion is an inlet 9 connected to a source of supply in the manner hereinafter described and at the upper end of the end plate 5 is an outlet 10 connected by a conduit 11 with converter tank 12. Leading from this converter tank 50 is a pair of discharge pipes 13 and 14, the latter of which connects with a reheater 15, and the

former is connected with the inlet pipe 9. Referring to Fig. 3, 1, 1a, 1b, 1c, 1d, 1e represent a plurality of furnaces; 18, 18a, 18b, etc. represent the circulating pumps; 19, 19a, 19b, etc. represent the motors to drive the same and 13, 13a, 13b, etc. and 11, 11a, 11b, etc. represent the circulation pipes. Disposed at right angles to the longitudinal axis of the chamber 12 are a plurality of baffle plates 34a, 34b, 34c, 34d, 34e; 33 is a main supply pump and 36 a motor to drive the same; 37 the intake to said pump and 35 is a feed pipe extending from the pump 33 and emptying into the chamber 12.

In the employment of this apparatus it is contemplated that the substance treated will circulate from the converter tank 12 freely through the furnace tubes 3 (Fig. 2) of the furnaces 1, 1a, 1b, etc. and back into the converter tank 12. In order to cause this circulation, pumps 18, 18a, 18b, etc. are employed for forcing the oil through the 70 inlets 9 of the heating tubes 3. As shown, these pumps are driven by motors 19, 19a, 19b, etc., both pumps and motors being mounted on the common bases 20, 20a, 20b, etc. The passage 75 through the various pipes is controlled by suitable valves, a cut-off valve 22 is in position on the pipe 14 for controlling the passage of treated oil from the converter tank 12 to the reheating still 15. Also the pipe 31 is provided with a cut-off valve 32 for controlling the flow of vapor from 80 the converter 12 direct to the condenser 29. A pipe 28 leading from the reheating still 15 to the condenser 29 is provided with a check valve 39. The outlet of the condenser coil 29 is provided 85 with a valve 40.

In starting the process, the intake 37 of the pump 33 is connected with a suitable supply of oil to be treated. Then the pump 33 is started and driven by the motor 36, pumping the oil into the converter 12 through the intake 35. As soon as sufficient oil is pumped into the apparatus, one third full more or less, the circulating pumps 18, 18a, 18b, etc. are all started and heat is applied in the furnaces 1, 1a, 1b, etc. Now the pump 33 is stopped, and the heat is applied in the furnaces 1, 1a, 1b, etc. until the pressure in the apparatus reaches the point that it increases out of proportion to the temperature, that is, when such a temperature is reached that pressure begins to rise without any further increase in temperature, the pressure in this case being that pressure due to the vapors from the hydrocarbons subjected to the treatment being generated by the heat. Now 95 this reacting temperature is maintained for a period of thirty minutes more or less according to 100 105 110

the character of the oil used. In any event, the temperature is maintained in the apparatus until a substantial amount of conversion products or gasoline-like products is obtained or formed in the oil itself. After this reacting time has been allowed, the valve 32 is opened sufficient to permit such incondensable gases to escape to prevent an excessive rise in pressure and the pump 33 again started so that the discharge of oil through the pipe 14 together with any discharge of vapor is replaced by the oil that is pumped in through the intake 35 simultaneously. If the pressure becomes excessive, the valve 32 is opened and some of the vapors are allowed to pass out through the pipe 31 into the condenser 29 and then discharged. If satisfactory condensation and separation of condensable vapors from non-condensable vapors is not accomplished in the condenser 29 when it is operated at atmospheric pressure, the valve 40 on the outlet of the condenser is partially closed so that sufficient pressure is built up in the condenser 29 so as to insure satisfactory separation of condensable from non-condensable vapors in the condenser 29. When sufficient oil has been discharged through the pipe 14 into the still 15 so as to partially fill it, fire is started and a distillate of gasoline or gasoline-like products is driven over through the vapor line 28 and into the condenser 29. Simultaneously vapor may also be delivered into the condenser 29 through the pipe 31 and valve 32. The length of the converter chamber 12 and the number of heating furnaces, 1, 1a, 1b, etc. will be determined entirely by the amount of oil that is to be treated in any one twenty-four hour period. The oil in this process, after it is started, is pumped in at such a rate that it will remain in the apparatus and be subjected to the reacting temperatures thirty minutes more or less according to the time required for producing gasoline or gasoline-like bodies. A pressure of from 100 to 800 pounds may be maintained, this varying with conditions.

It is self evident that the longer the converter chamber 12 and the more numerous the furnaces 1, 1a, 1b, etc., the more rapidly oil can be pumped in the apparatus and still allow the necessary reactive time for the production of the gasoline-like product. In order that the oil may not circulate by convection backward, baffle plates 34a, 34b, 34c, 34d, 34e, etc. may be placed in the vapor chamber 12 at right angles to its longitudinal dimension. A cross section of the converter chamber 12 with baffle plates 34, etc. is shown in Fig. 4. The height of this baffle plate is one-fourth the diameter of the vapor chamber 12, more or less according to the amount of oil that is being carried in the apparatus during the operation of the process.

The operation of this process provides means for continuous operation and recovery of gasoline and gasoline-like products during the operation of the process. It is also well known that if a hydrocarbon oil is being subjected to a cracking process or a conversion process, whereby light hydrocarbons are formed that there are also formed methane and other gases, which cannot be condensed into a liquid at atmospheric temperature. The amount of methane and non-condensable gas then is proportional to the amount of hydrocarbon products that is condensable into a liquid at atmospheric temperature. In the operation of this process, such pressure is produced that gasoline or gasoline-

like bodies may exist in the liquid phase, although the temperature may be somewhat high, that is, from 350 to 450 degs. C. or more. Now if the oil containing this gasoline is withdrawn through the line 14 and a less proportion of non-condensable vapor is withdrawn through the line 31 then the tendency is for an excessive amount of gasoline to be formed from the hydrocarbons inasmuch as the methane and other non-condensable vapors are not withdrawn to the same extent as the gasoline and, therefore, do not have to be formed to establish the chemical equilibrium in as great amount as would be the case if the non-condensable gas and the oil were entirely withdrawn at the same time. Laboratory apparatus operated in this way showed conclusively that, if during the operation of the process non-condensable gas was withdrawn, a larger amount of gas was formed than is the case were it not withdrawn. Also it was demonstrated that, if the gasoline were removed from the apparatus while the process was in operation, a somewhat larger yield was obtained than was the case when the non-condensable gas was removed at the same time. It was necessary, however, to remove some of the non-condensable gas as the pressure rose excessively high if it was not done, provided the gasoline was withdrawn and new oil pumped in during the operation of the process.

I claim as my invention:—

1. In an apparatus for treating petroleum, the combination with a plurality of tubes through which oil is circulated for the purpose of raising it to a conversion temperature, of an enlarged conversion chamber connected therewith, connections adapted to permit the continuous circulation of oil through the tubes and the conversion chamber, a still having communication with the conversion chamber, a pressure reduction valve in the communicating line between the conversion chamber and still, a single condensing means connected by separate lines to the still and conversion chamber for condensing the volatile material separated out in the respective stages.

2. In an apparatus for treating petroleum, the combination with an enlarged conversion chamber, of a plurality of tubes arranged in banks and connected to said chamber whereby a continuous flow of oil may be effected through the tubes and the conversion chamber, a still having communication with the conversion chamber, a pressure reduction valve in the communicating line between the conversion chamber and still, a single condensing means connected by separate lines to the still and conversion chamber for condensing the volatile material separated out in the respective stages.

3. An apparatus for treating petroleum oil comprising a plurality of furnaces through which oil is circulated for the purpose of raising it to a conversion temperature, an enlarged conversion chamber connected therewith, connections adapted to permit the continuous circulation of oil through the furnaces and conversion chamber, a still having communication with the conversion chamber, a pressure regulating valve in the communicating line between the conversion chamber and still, a vapor draw-off line connected to the conversion chamber having a regulating valve adapted to regulate pressures in the chamber and a condenser connected to the vapor draw-off line and to the still to condense the volatile material withdrawn from the chamber and still.

4. In an apparatus for treating petroleum, the combination with a plurality of furnaces through which oil is circulated for the purpose of raising it to a conversion temperature, of an enlarged conversion chamber connected therewith, connections adapted to permit the continuous circulation of oil through the furnaces and conversion chamber, means associated with the chamber for maintaining a regulated vapor pressure on the

oil in the chamber, a still having communication with the conversion chamber, a pressure reduction valve in the communicating line between the conversion chamber and still, condensing means connected directly to the still and pressure regulating means for condensing volatile material separated out in the respective stages.
